INTERNAL COMBUSTION ENGINE

Edwin C. Silvey, Jamaica, N. Y.

Application July 3, 1942, Serial No. 449,551

6 Claims.

(Cl. 123—50)

This invention relates to internal combustion engines and has for its primary object the provision of a power unit which is so characterized from a structural standpoint that it may be economically manufactured, assembled and installed for use to advantage in many fields, as for example, where natural gas or other suitable fuels are so abundantly available as to justify their being utilized, without regard to pronounced efficiency, in the development of power, provided the initial cost of a suitable power unit and the cost of maintaining such unit is relatively small as compared with the conventional types of present-day internal combustion engines.

Other objects and advantages of the invention will become apparent from the following description when taken in connection with the accompanying drawings in which Fig. 1 is a view partly in section and partly in side elevation of an internal combustion engine embodying the present invention; Fig. 2 is an end view of the engine as it appears from the right in Fig. 1; Fig. 3 is a vertical sectional view taken on line 3—3 of Fig. 1; and Fig. 4 is a wiring diagram of an ignition system adapted for use in the present instance.

Referring to the drawings, the numeral 5 indicates a suitable base or platform, on which the engine proper is supported, the engine being herein illustrated as including three cylinders 6, 7 and 8 although it will be understood that more or less cylinders may be employed, as desired, without departing from the spirit of the invention. Mounted on the base 5 are a pair of bearing standards 10 and 11, in the upper ends of which is journaled a power shaft 12 carrying at one end a flywheel 13 and at the other end a belt pulley 14.

To the shaft 12 is secured a grooved pulley 15 and a plurality of power-delivery wheels 16, 17 and 18, the peripheries of which, respectively, present oppositely disposed flanges 16a—16b, 17a—17b, 18a—18b. These flanges are so machined that their outer and inner faces are concentric with respect to the axis of the power shaft 12 in order that they may be effectively gripped intermittently by a plurality of self-energizing pawl-like driving lugs or dogs, herein-after referred to by the reference characters 85—85, 86—86 and 87—87 and more particularly described.

Mounted on the base 5 is a cylinder support 20, comprising end members 21, to the upper ends of which is connected a top plate 22. The top plate 22 is provided with a plurality of openings

24, within which are suitably secured the lower ends of the vertically disposed cylinders 6, 7 and 8, each cylinder being provided at its lower end with a frusto-conical or funnel-like fitting 25. These fittings are provided with inlet passages 26, 27 and 28 leading to the respective cylinders. The upper faces of the fittings 25 serve as valve seats for a plurality of valve balls 30, 31 and 32, which normally maintain the cylinders 6, 7 and 8 closed to their respective inlet passages 26, 27 and 28.

To the fittings 25, are connected a plurality of delivery conduits 34, 35 and 36, which are in turn connected to a conventional type of rotary distributor valve 37 of any conventional kind, to which leads a supply conduit 38, communication between which and the several delivery conduits is established successively by way of the distributor valve. The delivery conduit 38 leading to the valve 37 is connected to the outlet conduit 40 of any conventional type of compressor C, to which air and a suitable gaseous fuel is delivered by way of air and gas inlet pipes 41 and 42, respectively, which are equipped with control valves 44 in order that such volumes of gas and air may be admitted to the compressor C and thence to the cylinders 6, 7 and 8 as will effect complete or substantially complete combustion of the explosive mixture when ignited within the cylinders.

The shaft 45 of the compressor C is provided at its opposite ends with grooved pulleys 46 and 47, the former of which is connected by a belt 48 to the grooved pulley 15 carried by the power shaft 12, and the latter of which is connected by a belt 50 to a grooved pulley 51 secured to the shaft 52 of the rotary valve 37.

In order that the explosive mixture delivered to the respective cylinders 6, 7 and 8 in succession by way of the distributor valve 37 may be ignited, such cylinders are equipped with conventional spark plugs 54, suitably mounted in the side walls of the cylinders, and the electric circuits of which may be closed, according to standard practice, by a conventional type of commutator 55 herein illustrated as comprising a contact arm 56, carried by, but insulated from, the valve shaft 52 and adapted to be moved progressively into circuit-closing engagement with a series of equi-distantly spaced contacts 57, 58 and 60, carried by a contact supporting panel 61, of insulating material mounted on the base 5.

The ignition circuit employed in conjunction with the spark plugs 54 includes, as shown diagrammatically in Fig. 4, a plurality of branch

conductors 62, 64 and 65 connected to the contacts 57, 58 and 60, respectively, and leading to the spark plugs 54 of the respective cylinders 6, 7 and 8, the spark plugs being grounded through the cylinder walls, as shown at G. The contact arm 56 is connected to ground, as shown at G', by a conductor 66, in which is disposed a source of current, such as a battery B, from which current is delivered to the spark plugs 54 of the respective cylinders 6, 7 and 8 as the contact arm 56 is rotated in a clockwise direction, reference being had to Fig. 2.

It is to be understood that the closing of the circuits to the spark plugs 54 of the respective cylinders 6, 7 and 8 is so timed with relation to the operation of the valve 37 that communication between the compressor C and any given cylinder is severed immediately prior to the closing of the ignition circuit of the spark plug of that cylinder. Hence, it will be understood that any one of the valve-balls 30, 31, 32 that is elevated from its associated valve seat under the action of gas mixture flowing under pressure from the compressor C, by way of the valve 37, will fall by gravity to its seated position immediately prior to such time as the gas is ignited within a designated cylinder. Such valve-ball operation will, of course, obviate the burning of gas within the respective inlet conduits 34, 35 and 36 leading from the valve 37 to the cylinders 6, 7, 8 and will confine the explosion of gas to the cylinders according to their firing order.

In order that the explosions occurring within the cylinders 6, 7 and 8 may be effectively utilized to impart rotation to the power shaft 12, the cylinders are equipped with telescopic pistons 67, 68 and 69 which function somewhat in the manner of pistons employed in conventional types of internal combustion engines. The pistons 67, 68 and 69 are identical and each includes a top plate 70, having a depending peripheral skirt-like wall 71, the lower end of which is provided with an outwardly extending web 72, to the perimeter of which is connected an upwardly extending cylindrical wall 73, spaced from the wall 71 so as to provide an intervening air space S if desired. The walls 71 and 73, together with their associated web 72, constitute an annular vane V, loosely fitting and adapted for vertical reciprocation within an annular pocket P formed by a pair of spaced cylindrical walls 74 and 75 connected together at their lower ends by a web 76. It is to be noted that the inner walls 74 are spaced from the walls of the respective cylinders 6, 7 and 8, so as to provide air or liquid cooling spaces S' surrounding the several cylinders. The inner walls 74 are connected to the upper ends of the respective cylinders 6, 7 and 8 through the medium of annular flanges 77 which extend outwardly from the upper ends of the several cylinders.

Each of the three covers 70 of the piston 67, 68 and 69 carries a lug 80, to which one end of a link 81 is pivotally connected. Each link 81 is pivotally connected at its other end to the outer ends of a plurality of pairs of drive levers 82-82, 83-83 or 84-84, the inner ends of which drive levers are pivotally supported on the power shaft 12 to which the power delivery wheels 16, 17 and 18 are secured. As shown in Figs. 2 and 3, the pairs of levers 82-82, 83-83 and 84-84 are provided, respectively, with pivotally supported pairs of dogs 85-85, 86-86 and

87-87 the free ends of which engage the inner and outer surfaces of the power-delivery-wheel-flanges 16a-16b, 17a-17b and 18a-18b. As is apparent from Figs. 2 and 3, pairs of dogs 85-85, 86-86 and 87-87 are so angularly disposed with relation to the levers 82-82, 83-83 and 84-84 on which said dogs are carried that, as said levers are moved upwardly due to the rising of a piston 67, 68 or 69, the pairs of dogs impinge on and grip the flanges of the wheel 16, 17 or 18, thus causing the power shaft 12 carrying these wheels to be rotated in a clockwise direction as viewed in Figs. 2 and 3. However, when the force of the explosion is spent and the piston 67, 68 or 69 falls, thereby moving the pairs of levers 82-82, 83-83 or 84-84 downwardly, the pairs of dogs 85-85, 86-86 or 87-87 exert no gripping action on the wheel flanges, and consequently exert no counter turning effect on the power shaft 12 while the piston 67, 68 or 69 is falling or is in its lowermost position.

The engine embodying the present invention may be started by hand or mechanically, as will be understood, by rotating the power shaft 12 in a clockwise direction as viewed in Figs. 2 and 3, in which case the pistons 67, 68 and 69 remain at rest on the upper ends of the cylinders 6, 7 and 8. During the starting period, the compressor C delivers air and gas under slight pressure to one or another of the cylinders 6, 7 and 8, by way of the distributor valve 37, whereupon such air and gas mixture is ignited within one of the cylinders with the result that its piston 67, 68 or 69, as the case may be, is moved upwardly under the force of explosion causing the dogs 85-85, 86-86, or 87-87, as the case may be, to grip the flanges of one of the power-delivery wheels and thus rotate the power shaft 12. Once the engine is operating under its own power, the cylinders 6, 7 and 8 are fired in order, with the result that the power shaft 12 is subjected to successive turning forces in the manner just described in connection with the operation of one of the several cylinders.

Exploded gases from the cylinders 6, 7 and 8 escape through the substantial clearance spaces between the annular vanes V and the side walls of the pockets P. The clearance spaces just mentioned are of such limited extent that they afford a relatively slow-escape-passage for the exploded gases, thus allowing the expansion of the exploded gas within any given cylinder 6, 7 or 8 to be effectively translated into power of rotation, while at the same time permitting the escape of the exhaust gases at a sufficiently high rate to allow the piston 67, 68 or 69 of any given cylinder to return by gravity to its normal position of rest before such given cylinder is again conditioned for firing by being filled with the explosive mixture of gas and air.

According to the present invention, the major force of explosion is delivered directly to the pistons 67, 68 and 69, but it is to be noted that such major or direct force is supplemented by a reactionary force acting on the lower ends of the vanes V, the supplemental or reactionary force being accounted for by the sudden change in direction of flow of the exhaust gases as they travel downwardly and then upwardly through the pockets P.

Although only one embodiment of the present invention is herein shown and described, it will be understood that various modifications may be resorted to without departing from the spirit

of the invention or the scope of the following claims.

What is claimed is:

1. An internal combustion engine comprising a cylinder, means for delivering an explosive fuel to said cylinder, means for igniting and thus causing an explosion of said fuel within said cylinder, a piston tending to maintain a normal position of rest and adapted to be moved outwardly under the force of said explosion and adapted to move inwardly to its normal position upon release of exhaust from said cylinder, a power shaft, and gripper means operable only upon outward movement of said piston to couple said piston to said shaft and thereby effect unidirectional rotation of such shaft.

2. An internal combustion engine comprising an upwardly extending cylinder, means for delivering an explosive fuel to said cylinder, means for igniting and thus causing an explosion of said fuel within said cylinder, a piston forming with said cylinder a relatively slow-escape passage for exhaust and adapted to be moved upwardly under the force of said explosion and adapted to move downwardly under the action of gravity incident to release of exhaust from said cylinder by way of said passage, and means for utilizing said exhaust as it is released from said cylinder to effect a reactionary force on said piston.

3. An internal combustion engine comprising a cylinder, means for delivering an explosive fuel to said cylinder, means for igniting and thus causing an explosion of said fuel within said cylinder, a piston forming with said cylinder a relatively slow-escape passage for exhaust and tending to maintain a normal position of rest and adapted to be moved outwardly under the force of said explosion and adapted to move inwardly to its normal position upon release of exhaust from said cylinder by way of said passage, a power shaft, gripper means operable only upon outward movement of said piston to couple said piston to said shaft and thereby effect unidirectional rotation of such shaft and means for utilizing said exhaust as it is released from said cylinder to effect a reactionary force on said piston.

4. An internal combustion engine comprising a cylinder surrounded by an annular pocket, a piston overlying one end of said cylinder and

having an annular vane extending into said pocket and dimensioned with respect to such pocket for free longitudinal displacement therein incident to corresponding movement of said piston, 5 said vane forming with the wall of said pocket a slow-escape passage for exhaust, and means for effecting successive explosions of combustible fuel within said cylinder incident to each of which said piston is moved outwardly and pursuant to each of which the exhaust escaping by way of said passage is utilized to effect a reactionary force on said piston.

5. An internal combustion engine comprising a cylinder surrounded in spaced relation thereto 15 by an annular pocket, a piston overlying one end of said cylinder and having an annular vane extending into said pocket and dimensioned with respect to such pocket for free longitudinal displacement therein incident to corresponding 20 movement of said piston, said vane being provided substantially throughout its length with an annular air space and forming with the walls of said pocket a slow-escape passage for exhaust, and means for effecting successive 25 explosions of combustible fuel within said cylinder incident to each of which said piston is moved outwardly and pursuant to each of which exhaust escaping by way of said passage is utilized to effect a reactionary force on said piston.

6. An internal combustion engine comprising a cylinder, an inlet conduit communicating with the bottom of said cylinder and provided with a valve seat, a valve ball cooperating with said valve seat thereby forming a check valve substantially preventing the passage of gases from said cylinder into said conduit, a compressor for delivering a combustible fuel mixture to said cylinder through said check valve, means for igniting and thus causing an explosion of said 40 fuel mixture within said cylinder, a piston tending to maintain a normal position of rest at the lower limit of its travel and adapted to be moved upwardly under the force of said explosion and fall downwardly to its normal position when the 45 force of the explosion in said cylinder is spent, a power shaft, and gripper means operable only upon outward movement of said piston to couple said piston to said shaft and thereby effect unidirectional rotation of said shaft.
